UNITED STATES PATENT OFFICE.

JOHN FREDERICK WELLS, OF CAIRO, EGYPT.

PROCESS AND APPARATUS FOR CARBONIZING WOOD AND OTHER CARBONACEOUS MATERIAL

1,383,888.

Specification of Letters Patent.

Patented July 5, 1921.

Application filed December 16, 1919. Serial No. 345,411.

To all whom it may concern:

Be it known that I, JOHN FREDERICK WELLS, a subject of the King of Great Britain, of 36 Sharia Falaki, in the city of Cairo, Egypt, have invented new and useful Improvements in Connection with Processes and Apparatus for Carbonizing Wood and other Carbonaceous Material, of which the following is a specification.

10 This invention relates to a carbonizing wood, vegetable matter, peat, coal, lignite or other carbonaceous material.

The object of the invention is to provide an improved carbonizing process of a continuous character which shall enable charcoal to be produced from waste vegetable matter such as scrub, brush, cotton sticks, straw, and the like, in which the heat, or a portion of the heat, evolved by the combustion of the volatile matter is utilized for effecting carbonization.

According to this invention the material to be treated is passed into a vertical chamber and the heat for the distillation of the mass is obtained from the combustion of a substantial proportion of the heavy hydrocarbons that still remain in the wood, coal or other material on its arrival at or approaching the grate, the temperature being regulated to produce this effect by varying the speed of removal of the charcoal or other material and the suction on the outlet of the apparatus. At the moment when the last portion of the volatile constituents is being consumed the carbonized material at the bottom of the chamber is withdrawn. As the carbonized material is withdrawn its place is taken by a portion of the descending fuel from which the lighter volatile constituents have been driven off by the heat from the combustion of the gases or volatile products rising from the bottom of the chamber. The process is thus of a continuous character and combustion is effected only at the bottom of the carbonizing chamber, the air supply being limited to that required to support such combustion. The moment when the last portion of the volatile constituents is being consumed is approximately the moment when the products of combustion cease to be of a dark color.

Apparatus suitable for carrying out this invention is illustrated diagrammatically in the accompanying drawing which is a view of the apparatus in vertical section.

The apparatus comprises a central shaft or hopper *a* into which the material to be treated is delivered and falls direct into the carbonizing chamber *b*. The lower end of this chamber is provided with a grate *c* 60 inclined downwardly and pivotally mounted opposite to rotatable blades *c'* which latter when rotated serve to remove the carbonized material from the grate *c* and pass it outward. The hopper *a* is divided into upper 65 and lower chambers *a'* *a''* separated by a horizontal partition *a³* having a central opening *a⁴*. Within the lower chamber *a'* is formed an annular space *a⁵* the depth of said chamber and into this annular space 70 the gases evolved from the combustion of the material pass by way of openings *a⁶* at the upper end of the chamber *a'*.

The gases are drawn away from the bottom of this annular space by a pipe *a⁷*. In 75 the vertical axis of the hopper *a* there may be arranged a rod or bar *d* which passes through the chambers *a'* *a''* and is provided as to its central portion with projections *d'* inclined downwardly. The upper end of the 80 bar *d* passes through a ball-and-socket joint *a⁸* in the cover *a⁹* of the hopper *a* and is connected with suitable means for reciprocating the bar to push the fuel from the upper chamber *a'* into the lower chamber *a''* 85 through the opening *a⁴*.

Assuming the apparatus above described to be in operation the chambers *a''* and *b* will contain the material under treatment in different stages of carbonization. The material in the chamber *a''* is subject to the heat of the gases evolved from the combustion of the material in the chamber *b* and also to the heat of the gases in the annular space *a⁵* surrounding the chamber *a''*; the material 90 in this chamber being thus partially carbonized. The material in the chamber *b* is in a further state of carbonization and while the last portion of the volatile constituents is being evolved the carbonized material is 100 withdrawn by rotating the paddles *c'* and causing the charcoal to be drawn through the reservoir *e* containing water.

By means of this apparatus I am enabled to produce the maximum of low temperature 105 charcoal, or I may produce a lower percentage of charcoal at a higher temperature by increasing the quantity of gas or charcoal burned and withdrawing the charcoal at a lesser rate. In the latter case the quan- 110

5 tity of gas evolved is increased and is at be treated, effecting combustion of the gases its maximum at the moment of complete or volatile products at the bottom of the gasification of the charcoal formed, the ap- chamber by the admission of air below the paratus then working as an ordinary form grate, and withdrawing the carbonized material from the bottom of the chamber sub- 20

25 The working of the apparatus is controlled by regulating the rate or velocity at which the gases are drawn from the annular chamber a^o .

10 10. What I claim as my invention and desire to secure by Letters Patent is:—

The continuous process for carbonizing wood, vegetable, peat, coal, lignite and other carbonaceous material, consisting in charg- 25

15 ing a vertical chamber with the material to

JOHN FREDERICK WELLS.
